LADY'S HANDBAG

Robert S. Berens, Brooklyn, N. Y.

Application June 30, 1953, Serial No. 25,737

Term of patent 3½ years

(Cl. D87—3)

To all whom it may concern:

Be it known that I, Robert S. Berens, a citizen of the United States and a resident of Brooklyn, county of Kings, city and State of New York, have invented a new, original, and ornamental Design for a Lady's Handbag, of which the following is a specification, reference being had to the accompanying drawing forming a part thereof.

In the drawing:

Fig. 1 is a perspective view of a lady's handbag showing my new design;

Fig. 2 is a rear elevational view thereof; and
Fig. 3 is an end elevational view, the opposite end being identical.

I claim:

The ornamental design for a lady's handbag, as shown and described.
